FOUNTAIN PEN

Henri Goulot, Colombes, France, assignor to
Joseph Frentzel, Paris, France

Application February 26, 1946, Serial No. 650,202
In France June 7, 1945

4 Claims. (Cl. 120—47)

1

My invention has for its object improvements in fountain pens provided with a piston operated filling device. Said invention covers more particularly means for increasing the capacity of the ink container in fountain pens of this type, while it allows an easy and speedy filling through a single operation.

To this purpose, my improved fountain pen is chiefly characterized by the fact that the filling piston moving inside the fountain pen body is formed by a tubular member housing a very long spring held between the bottom of the piston and the opposite end of said body; this spring is guided by a central rod and is designed in a manner such that when the piston is in its inner or depressed position, it fills substantially the entire space comprised between the inner surface of the piston and the guiding rod whereby the hollow piston is capable of acting in the same manner as a solid piston for completely forcing the air out of the container or body of the fountain pen.

My invention has also for its object means for providing for perfect fluid tightness of the piston.

Other objects and advantages of my invention will appear in the reading of the following description and in the examination of accompanying drawing illustrating diagrammatically and solely by way of example a form of execution of the invention.

In said drawing:

Fig. 1 is a cross-sectional view of the whole fountain pen.

Fig. 2 is a cross section at a larger scale of a form of execution of the fluid-tight arrangement for the piston.

The fountain pen provided with a filling piston executed in accordance with my invention includes a tube 1 forming the body or container of the pen and to the end of which is screwed the section 2 carrying the nib 3 while the other end of the tube 1 is screwed into a guiding plug 4 inside which the filling piston 5 is adapted to slide.

According to my invention, said piston is hollow and its outwardly closed inner capacity opens into that of the tube 1. Its length is such that in normal position it projects considerably to the outside of the tube while during the filling operation it may be urged sufficiently far for its inner end to abut against the bottom of the container. The projecting part of the piston is protected by a hood or cap 6 screwed over the guiding plug 4.

Said piston may slide with slight friction inside the body 1 of the pen and a suitable packing 7

2

the detail of which is disclosed hereinafter is provided for ensuring perfect fluid tightness of the piston. The piston carries moreover a flange or stop shoulder 8 abutting against the guiding plug 4 at the end of its outward motion.

According to an important feature of my invention, there is provided inside the piston 5, an elongated spring 9 which may be made of stainless steel or the like inoxidisable metal and said 10 spring bears on one hand against the bottom of the piston 5 and on the other hand against a washer 10 bearing in its turn against the nib carrying section 2 of the pen. The washer 10 is provided with a recess 11 and with ports 12 15 adapted to provide a passage for the ink from the inner chamber 13 or container of the pen into the pen feeding duct and reversely.

The washer 10 carries also a rod 14 serving as a guiding member for the spring 9. This spring 20 is established in a manner such that at the end of the compressional stroke of the piston 5, the coils of said spring may be in close contact with one another so as to fill substantially the entire space comprised between the rod 14 and the 25 inner wall of the piston.

By reason of this particular construction, the air is completely forced out of the container when the piston is urged into the tube 1 up to the end of its allowed stroke. Consequently during the 30 return or suction stroke, the ink may fill completely the space open to it inside the body 1 and inside the hollow part of the piston 5. By reason of the long stroke of the piston, it is possible to suck in a large volume of ink in a single pumping 35 stroke.

I obtain thus a large capacity fountain pen which requires for its filling a single reciprocation of the piston 5 instead of requiring repeated operation as in most fountain pens presently on the market and provided with a pump for filling purposes, the filling mechanism occupying in such fountain pens a considerable bulk.

Further, since spring 9 is comparatively long and has therefore a great number of turns, the 45 difference between the resistance offered by said spring at the beginning and at the end of the movement is relatively small.

Lastly the execution of the fountain pen as a whole is particularly simple. In particular the 50 body 1 of the container assumes the shape of a tube open at both ends and may therefore be easily and accurately bored, which is of particular importance for the fluid-tightness of the piston.

Fig. 2 shows a particularly advantageous form 55 of execution of the water-tight ring-shaped pack-

ing 7 for the piston 5; this packing is held by a groove 15 in the piston having a diameter d and forming two shoulders 15' for securing the fluid tight packing; the latter is made of an elastic material which allows its easy insertion. It shows two bevelled lips 16 and 17 at the opposite outer edges of the packing; one of said lips 16 provides for watertightness in the direction of the arrow f1 whereby it prevents the ink from flowing out of the chamber or container 13 while the other 17 provides for fluidtightness in the opposite direction which is that of the arrow f2 so as to prevent the air from returning into the chamber 13 during the filling of the pen through the operation of the piston.

An annular groove 18 provides a greater elasticity for the ring-shaped packing in its medial plane and it prevents it moreover from forming in said plane a bead or swelling which would detrimentally affect the ease of operation. Moreover, according to one of the chief features of the invention, said groove may be filled with lubricating material such as oil or paraffine which makes the sliding of the piston easier and allows a very great ease of operation for the filling piston: e. g. such a lubricating material may be a pasty compound of graphite and neutral grease having no action whatsoever on the ink. This pasty compound forms a definite layer on the inner wall of the fountain pen without ever mixing with the ink.

The diameter at the outer edge of the lips 16 and 17 is provided slightly larger than the inner diameter of the container constituted by the tube 1 so that the elasticity of these lips may compensate for the unavoidable defects in boring and allows in fact the bore to be executed with a grade of machining which is lower than that required in usual piston fountain pens in which the fluid tight packing is constituted by cork or a rubber ring of a different shape. This arrangement allows also executing a simple one-piece piston without any nut or screw for securing the fluidtight packing. It reduces also to the indispensable minimum the difference between the inner and outer diameters D and d of the packing 7; this allows the piston to receive a sufficient diameter for it to be formed as a hollow member with a sufficient inner bore.

Lastly it is apparent that the execution of the piston and of its packing is extremely simple and that the mounting of the ring 7 on the piston is very easy, which allows changing it very easily when required.

Obviously my improved fountain pen described hereinabove and illustrated in the drawing has been given out solely by way of example. It may receive certain modifications in its details of execution without the general principle underlying my invention being altered thereby. Thus in particular the section 2 instead of being screwed into the body 1 may form a single member with said body. Similarly the rod 14 and the washer 10 instead of being formed in one may be divided into two distinct parts rigidly secured to one another.

What I claim is:

1. A fountain pen comprising a hollow body, a nib-carrying end thereof, a hollow piston arranged for sliding inside said hollow body and the inner capacity of which opens into the same, the length of the piston being slightly greater than that of its stroke inside said hollow body, in combination with a spring arranged axially

in the body and the piston and bearing against the nib-carrying end and the closed end of the piston, respectively, and a rod engaged within the spring and passing axially through the body

5 and a portion of the hollow capacity of the piston, said spring and said rod occupying substantially the whole of the inner capacity of the piston when the spring is compressed by driving the piston the maximum distance within said hollow body.

2. A fountain pen as claimed in claim 1 wherein the spring-engaging rod is solid and is integral with the nib-carrying end.

3. A fountain pen comprising a hollow body, a 15 nib-carrying end thereof, an outwardly grooved hollow piston arranged for sliding inside said hollow body and the inner capacity of which opens into the same, the length of the piston being slightly greater than that of its stroke inside 20 said hollow body, in combination with a spring arranged axially in the body and the piston and bearing against the nib-carrying end and the closed end of the piston, respectively, and a rod engaged within the spring and passing 25 axially through the body and a portion of the hollow capacity of the piston, said spring and said rod occupying substantially the whole of the inner capacity of the piston when the spring is compressed by driving the piston the maximum 30 distance within said hollow body, and a fluid-tight packing carried by the inner end of the piston inside the groove on the outer wall thereof, said packing having two lips extending laterally of the length of the pen directed forward and 35 backward from the main part of the packing and adapted to slide over the inner surface of the body.

4. A fountain pen comprising a hollow body, a nib-carrying end thereof, a hollow piston arranged for sliding inside said hollow body and the inner capacity of which opens into the same, the length of the piston being slightly greater than that of its stroke inside 40 said hollow body, in combination with a spring arranged axially in the body and the piston and bearing against the nib-carrying end and the closed end of the piston, respectively, and a solid rod secured to the nib-carrying end of the hollow body engaged within the spring and passing axially through the 45 body and a portion of the hollow capacity of the piston, said spring and said rod occupying substantially the whole of the inner capacity of the piston when the spring is compressed by driving the piston the maximum distance within said 50 hollow body.
